TABLE LIGHTER BASE

Peter C. Kenney, Wellesley, and Peter V. Tremblay,
Hingham, Mass., assignors to The Gillette Company,
Boston, Mass.

Filed Nov. 22, 1972, Ser. No. 308,818

Term of patent 14 years

Int. Cl. D27—05

U.S. Cl. D48—27 R

Fig. 1

Fig. 2

FIG. 1 is a perspective view of a table lighter base showing our new design;

FIG. 2 is a front elevational view thereof;

FIG. 3 is a side elevational view, the opposite being substantially a mirror image thereof;

FIG. 4 is a rear elevational view thereof;

FIG. 5 is a bottom plan view thereof; and

FIG. 6 is a top plan view thereof.

We claim:

The ornamental design for a table lighter base, substantially as shown and described.
